UNITED STATES PATENT OFFICE.

CLARENCE O. HARMON, OF TOLEDO, OHIO, ASSIGNOR OF ONE-HALF TO FREDERICK B. DE FREES, OF TOLEDO, OHIO.

ELECTRIC HEATER.

1,219,940.

Specification of Letters Patent. Patented Mar. 20, 1917.

Application filed February 28, 1916. Serial No. 30,767.

To all whom it may concern:

Be it known that I, CLARENCE O. HARMON, a citizen of the United States of America, residing at Toledo, Lucas county, Ohio, have invented a new and useful Electric Heater, of which the following is a specification.

This invention relates to radiation devices.

10 This invention has utility when incorporated in heaters, as electric heaters, for cooking purposes. This invention has as one of its objects the production of a heat radiation device.

15 Referring to the drawings:

Figure 1 is a fragmentary plan view of an embodiment of the invention in a heater for a stove or hot plate;

Fig. 2 is a side elevation with parts broken away of the heater of Fig. 1;

Fig. 3 is an end elevation with parts broken away of the heater of Fig. 1;

Fig. 4 is a section of the conductor main with one of the branch conductors mounted thereon ready to be engaged with the insulator support;

Fig. 5 shows the conductor main and branch conductor of Fig. 4 interengaging with a pair of insulator strips, as mounted 30 in the heater;

Fig. 6 is a plan view, with parts broken away, of a double deck arrangement of the heater elements, a circular unit as against the showing of a rectangular single deck 35 unit in Fig. 1;

Fig. 7 is a side elevation with parts broken away of the heater of Fig. 6, showing its mounting in a heat retaining pocket; and

Fig. 8 is a section of a conductor main, 40 showing a conductor branch mounted thereon interengaging with a pair of insulator strips, this conductor branch being an elevation of the opposite side from the conductor branch of Fig. 5.

45 The heating unit comprises the housing or embracing frame embodying the front member 1, the rear member 2, and the end members 3. Each of these members comprises the central channel 4 and the edge channels 5 and 6. The side members 1 and 2 are provided with tongues 7 which may protrude through the end members 3 and be bent over to lock the frame in an assembled unit of light and rigid structure.

The upper edge channel 5 serves to interengage with the grid 8 protecting the central heating units from attack as well as furnishing a support for vessels or articles being heated. The channel 6 at the lower side carries the grid 9 provided with the legs or feet 10 supporting the heating unit. Disposed in the central channels 4 are imperforate insulating strips 11, say of mica, of a contour about one-half the depth of the channels 4. In the end channels 4, over the strips 11, are placed insulation strips 12, and parallel thereto throughout the extent of the heater are the similar intermediate insulation strips 12.

The heating unit may be provided with a terminal 13 from which may extend the conductor main 14 midway between a pair of strips 12 from the frame side 1 to the frame side 2. At the frame side 2, the main 14 is disposed in the channel 4 against the insulating strip 11 and passes through a notch or seat 15 in the intermediate insulation strip 12 and from thence passes back to the frame side 1 between the second insulation strip and a third insulation strip 12. This progress of the conductor main 14 continues throughout the extent of the unit and the main is then brought back by the insulated conductor 16, which may be held in position by the inwardly pressed loops 17 in the side frame 1 in its course back to the conductor 17 in the terminal 13. The main conductor 14 has thereabout loops 18 of conductor branches, having the arms 19 with the reverse bend sections 20 configured to enter openings 21 in the insulation strips 12. With these sections 20 engaging the strips 12, the free ends 22 of the branch conductors are bent into interlocking relation with the insulator strips 12. There is thus formed an interlocking engagement between the strips 12 and the conductor main 14, giving rigidity to the structure and medial support between the elements thereof to further stiffen the grouping. Alternate opposite arms 19 of the branches 18 are staggered as shown in Figs. 5 and 8. These branches 18, 19, 20, 22, are heat conductors and accordingly, notwithstanding they are not in the

direct circuit of the main 14, coöperate with the electrical conductor 14 to radiate heat therefrom.

The circular unit of Figs. 6 and 7 has the 5 housing frame 23 provided with the upper channel 5 for the protecting grid 24 and is provided with a pair of intermediate channels 4. The housing 23 has the extension 25 from the channel 5 with the embracing portion 26 to engage the side walls 27 of the containing vessel having the bottom 28 with seepage openings 29 therethrough. This vessel 27, 28, may have the insulation packing 30 surrounding the housing 23 to retain 15 the heat in the heating unit, while over the openings 29 in the bottom 28 may be disposed an insulating fabric 31, say of sheet asbestos, which will resist the passage of heat from the unit and still allow the seepage of liquids spilt from cooking to pass through the openings 29. The intense heat of the unit serves to dry and harden other material so that the device may be readily cleaned by shaking in reverse position.

25 The terminal 32 has the insulated conductor 33 extending to the main 34 sustained by heat radiation branches or conductors 18, with arms 19, alternately staggered in engagement with insulating strips 12. This main 34 passes to and fro between pairs of insulating strips in the circular unit in a similar manner to the main 14 in the rectangular unit. This main 34 is returned by the insulated conductor 35 to the conductor 36. From the conductor 36 extends the insulated conductor 37 to the second or lower deck of the heat radiation elements where it communicates with the conductor main 38 extending similar to the conductor main 34 but at right angles thereto and therebelow between pairs of insulating strips 12, the intermediate strips being parallel to each other and at right angles to the superposed strips 12 in the upper deck of this heating unit. 45 This conductor main 38 is returned by the insulated lead 39 to the conductor 40.

By controlling switches so that electric current is passed from conductor 33 to conductor 36, only the upper deck of the heating unit is in service. With the circuit closed from the conductor 33 to the conductor 40, each deck of the heating unit is in service. It is accordingly possible to get two intensities of heat very readily from 55 this compact, light and rigid construction.

The interlocking staggered disposal of the laterally extending arms from the heat conductor mains permits of a light weight, long life, stiff construction, with uniform radiation for heat on a most efficient basis.

What is claimed and it is desired to secure by Letters Patent is:

1. An electric heater comprising a straight section of electric conductor, sustaining means therefor including intermediate its

length transverse dead end heat radiation members, and insulation supporting means for the sustaining means.

2. An electric heater comprising an electric conductor forming parallel straight sections, insulation strips between the straight sections of the conductor, and heat radiation members engaging the strips and conductor along the straight sections. 70

3. An electric heater comprising a continuous electric conductor forming parallel straight sections intermediate its extent, insulation strips uniformly spaced between the straight sections, and wire anchors along the straight sections each interlocking with a straight section and two insulation strips. 75

4. An electric heater housing comprising a sheet metal member provided with a flange along one edge thereof, a groove parallel therewith, an insulation strip carried by the groove, heat radiation means mounted by the insulation strips, and an electric conductor supported by the heat radiation means. 80

5. An electric heater comprising a sheet metal housing provided with an endless inwardly opening groove, and a grid carried by the groove, said housing having a second groove spaced from the first groove and electric heater means carried by the second groove parallel with the grid. 85

6. An electric heater comprising a sheet metal housing providing opposing groove means and extending therebetween parallel insulation strips carried by the groove means. 90

7. An electric heater comprising a sheet metal housing providing opposing groove means, parallel perforate insulation strips carried by the groove means, and heat radiation means anchored in the perforations of the parallel insulation strips for stiffening the strips. 95

8. An electric heater comprising a sheet metal housing providing opposing groove means, parallel insulation strips carried by the groove means, heat radiation means anchored in the parallel insulation strips for stiffening the strips, and an electric conductor stayed by said radiation means for rigid fixed extent between the parallel insulation strips. 105

9. An electric heater housing comprising opposing groove means, parallel insulation strips carried by the groove means, heat radiation means anchored in the parallel insulation strips, and an electric conductor stayed by said radiation means and interlocked by said radiation means with the insulation strips for combined rigidity support. 110

10. A straight electric conductor section, a heat radiation wire embracing said conductor section and extending radially therefrom, and insulation strips parallel with the conductor wires and forming terminal an- 115

chors for the heat radiation means whereby the electric conductivity is confined to the electric conductor while the heat radiation is dissipated from said conductor by the radiation means.

5. 11. An electric heater comprising a main electrical conductor, transverse supporting wires having dead terminals and supporting

means engaging said dead terminals to thereby anchor the main electrical conductor 10 for free heat dissemination from said electrical conductor and the transverse supporting wires.

In witness whereof I affix my signature,

CLARENCE O. HARMON.
